UNITED STATES PATENT OFFICE.

ANDREW W. BISCHOFF, OF RANKIN, ILLINOIS.

FLY-PAPER HOLDER.

1,080,249.

Specification of Letters Patent.

Patented Dec. 2, 1913.

Application filed February 20, 1913. Serial No. 749,685.

To all whom it may concern:

Be it known that I, ANDREW W. BISCHOFF, a citizen of the United States, residing at Rankin, in the county of Vermilion and State of Illinois, have invented a new and useful Fly-Paper Holder, of which the following is a specification.

This invention relates to fly paper holders, and for its primary object aims to provide a suitable holder for fly paper, which will also serve as a guard, so that accidental contact with the fly paper may be avoided.

As a further object, the present invention contemplates the production of a fly paper holder embodying a board capable of having a sheet of fly paper attached to both faces thereof, the fly paper being protected by means of wire arches attachable to the board.

Among its other objects, the present invention has in view, a holder of the character indicated, which shall be simple, substantial, durable and inexpensive in construction; which may hold the fly paper in position against accidental displacement or detachment from the holder; which may hold the fly paper at various adjustments, or in an arched position; and which shall be convenient, serviceable and efficient in use.

With the foregoing general objects outlined, and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawings, wherein corresponding reference characters have been employed to denote corresponding parts, and wherein:

Figure 1 is a perspective view of a fly paper holder constructed in accordance with the present invention. Fig. 2 is a side elevation thereof. Fig. 3 is an end elevation. Fig. 4 is a sectional detail on an enlarged scale.

Referring specifically to the drawings, the numeral 5 designates the board forming the body of the holder, which is preferably constructed of pulp, but may be con-

structed of fiber, papier-mâché, or any other suitable material, the said board being rectangular in contour.

Along the longitudinal edges of the board 5 and on the opposite faces thereof, are clenched two series of hook eyelets 6, the two series being parallel and lying along the longitudinal edges of the fly paper when the fly paper is placed against the board. 60 Eyelets 7 are also clenched to the board 5 at the end portions of the board and serve as means for suspending the board, when desired or beneficial. 65

In connection with the board 5, there are 70 employed a plurality of guards, each of which comprises a wire arch, having outwardly projecting hooked feet and resilient fly paper engaging portions projecting inwardly from the feet. Two forms of the 75 guards have been shown in the drawings, the first and simplest form comprising a wire arch 8 provided with the outwardly projecting hooked feet 9 and the resilient portions 10 projecting inwardly from the 80 feet 9 and provided with the bent back extremities 11 forming finger holds. The second form of guard comprises a wire arch 8^a having a double bend 8^b at its intermediate portion, and having the outwardly projecting hooked feet 9, which have the respective inwardly projecting resilient portions 10^a and 10^b. The portion 10^a of the 85 wire arch 8^a is provided with an upstanding loop 11^a providing a finger hold and also 90 increasing the resiliency of the portion 10^a, the extremity of the said portion being downturned to provide a spur 12 for biting or engaging the fly paper. The portion 10^b of the arch 8^a is bent into a loop 11^a providing a finger hold and fly paper engaging member. Either form of guard may be used throughout, or both forms may be employed in one holder, according to the whim of the user. The second form is desirable, 100 in that the double bend 8^b provides a greater resiliency of the wire arch and the spur 12 provides more efficient means for engaging the fly paper, the portion 10^a also being more resilient or flexible. 105

In use, the sheet of fly paper, of the sticky variety, is placed on the upper face of the board 5 between the two series of hooks 6, and the guards are then positioned on the board by the engagement of the hooked feet 110 9 with the hooks 6, the resilient portions being brought into engagement with the fly.

paper along the edges thereof and the attachment of the wire arches being facilitated by the finger holds. Either one sheet of fly paper may be held upon the upper 5 face of the board, or two sheets may be held upon the opposite faces thereof, as desired or beneficial. It will be noted, that when the wire arches are attached to the board, the fly paper engaging portions in engaging 10 the fly paper will retain same in position against accidental displacement, it therefore being possible to adjust the fly paper in various positions. In this manner, the fly paper may be arched transversely as indicated in dotted lines in Fig. 1, so as to more effectively attract the flies or other insects. This holder may be set upon any suitable object, and when the wire arches are attached to the bottom of the board, the 15 lower arches will support the board above the object, or the board may be suspended from any suitable object by means of the eyelets 7, as will be apparent.

This holder may be employed in a variety 20 of ways, such as need not be itemized at length, and from the foregoing taken in connection with the drawings, it will be seen that the objects aimed at are attained in an efficient manner, the holder providing 25 a desirable one for the purposes to which it

is designed. The holder may also be collapsed when not in use for compactness for shipment or storage.

Having thus described the invention, what is claimed as new is:—

1. A fly paper holder embodying a board having parallel series of hooks designed to receive the fly paper therebetween, and resilient arched guards having feet engageable with the respective hooks and having 40 resilient fly paper engaging portions projecting inwardly from the feet.

2. A fly paper holder embodying a board, parallel series of hook eyelets clenched to the board and designed to receive the fly 45 paper therebetween, and a plurality of guards each comprising a wire arch having outwardly hooked feet engageable with the said hook eyelets and having resilient fly paper engaging portions projecting inwardly from the feet, the said resilient portions being provided with finger holds.

In testimony that I claim the foregoing as my own, I have hereto affixed my signature in the presence of two witnesses.

ANDREW W. BISCHOFF.
